WILLIAM F. SCHMIDT, OF DETROIT, MICHIGAN, ASSIGNOR TO MOYER-SHAW MFG. CO., OF DETROIT, MICHIGAN, A CORPORATION OF MICHIGAN.

AIR AND POP GUN.

1,178,268.

Specification of Letters Patent.

Patented Apr. 4, 1916.

Application filed November 19, 1915. Serial No. 62,263.

To all whom it may concern:

Be it known that I, WILLIAM F. SCHMIDT, a citizen of the United States, residing at Detroit, county of Wayne, State of Michigan, have invented a certain new and useful Improvement in Air and Pop Guns, and declare the following to be a full, clear, and exact description of the same, such as will enable others skilled in the art to which it pertains to make and use the same, reference being had to the accompanying drawings, which form a part of this specification.

This invention relates to air and pop guns and has for its object a gun which requires no breaking or cocking by a separate lever to set it for the next discharge. The pulling of one trigger not only sets the gun for discharge but actually trips the holding lever and discharges the gun.

In the drawings.—Figure 1 is a side elevation. Fig. 2 is a view of the interior operating parts. Fig. 3 is a view of the barrel showing the extended plunger rod. Fig. 4 is a rear edge view of the plunger-retracting lever. Fig. 5 is a rear edge view of the trigger lever.

The gun is here shown as a pop gun which discharges a cork *a* from the barrel *b* when the plunger *c* compresses the air ahead of it. The plunger *c* is propelled forward to compress the air by the strong coiled spring *d* that engages about the plunger rod *e*. The operating parts are contained in a housing shaped to simulate a pistol and comprising a pair of half shells *f*, *f* which screw together. The plunger rod extends to the rear of the barrel and is flattened and slotted at *g*. In this slot extends the upper end of the plunger-retracting lever *h*. This is provided on its forward edge with a turned-over contact lip *i*. This is adapted to be wiped by the contacting projection or hook *j* of the trigger lever *k*. This trigger lever *k* is in general outline T-shaped with the bottom part of the stem crooked slightly to the right for the convenience of grasp. The T when in normal inoperative position is really turned-over on its side and its fulcrum point at the left hand end of the bar of the T. From the left hand end of the bar of the T a small integral lug *m* projects to receive one end of the flat spring *n* that serves to return the trigger lever to its initial position after the projection *j* has

dropped off the contact lip *i* to allow the 55 operation of the gun.

The operating parts work as follows: The handle portion of the T-like trigger lever is pulled toward the rear of the gun in the customary fashion. The projection *j* 60 wipes along the contact lip *i*, gradually forcing back the plunger-retracting lever as the projection *j* climbs toward the top of the contact lip *i*. When the projection *j* reaches the top of the contact lip the maximum compression of the spring *b* is had. When the top of the contact lip is reached the projection *j* is out of the way of the contact lip and the plunger-retracting lever *h* is now free to travel forward and hence 70 the strong spring *d* is released and the plunger shoots forward with considerable force and velocity. By reason of the contact lip *i* being offset from the plane of the plunger-retracting lever *h* and by reason of the projecting point on the projection *j* being offset from the arm portion thereof, as apparent in both Figs. 4 and 5, the trigger lever may return to its initial position as the point *j* swings to the rear and under the 80 contact lip *i* to a position just forward of it.

It will be noted that the plunger-retracting lever *h* has a loose pivoting at its bottom, a pivot pin passing through a slot in the lever. A spring *o* normally tends to keep 85 the plunger-retracting lever from rising or increasing its length above its pivot. This is an important feature for it will be evident that in order that the trigger lever can get back to its initial position the projecting pin 90 *j* must pass under the lower end of the contact lip *i* and must lift this. This it does by reason of the peculiar pitch and bevel of the contact point *j* and the inclination of the plunger-retracting lever *h* and the contact lip. However, after it has passed under the contact lip the bevel on the under side of the contact point and the inclination of the lip and plunger-retracting lever is such that when the projection *j* again contacts 100 the contact lip it wipes the outside surface of it and climbs the same to retract the contact lever in the manner already described, when it again slips off the top and allows the discharge of the gun.

I have shown and described my invention in connection with a pop gun but it is obviously applicable to any gun in which the

propelling force is air pressure generated by a plunger forced forward by a spring.

What I claim is:

1. In a gun of the class described, the combination of a barrel provided with a chamber, a plunger reciprocating in said chamber, a spring for propelling the plunger ahead, and means for retracting the plunger, compressing the spring and releasing it by the single action of a single lever, comprising a plunger-retracting lever suitably connected with a plunger and a trigger lever adapted to engage the plunger-retracting lever to retract the same and when the same is retracted disengage itself therefrom.

2. In a gun of the class described, a barrel provided with a chamber, a plunger reciprocating in said chamber, a spring for propelling the plunger forward, a plunger-retracting lever suitably connected with said plunger and a trigger lever whose retraction causes a portion of the trigger lever to wipe a portion of the plunger-retracting lever and retract the same to a given point where the trigger lever slips off from the plunger-retracting lever to allow the discharge of the gun.

3. In a gun of the class described, the combination of a barrel provided with a chamber, a plunger reciprocating in said chamber, a spring for propelling the plunger forward, a plunger-retracting lever provided with an offset contact lip and suitably connected with the plunger, and a trigger lever provided with an offset projection adapted to wipe and climb the offset contact lip to retract the plunger lever until the offset projection of the trigger lever reaches the top of the contact lip whereupon the lever is released and allows the discharge of the gun.

4. In a gun of the class described, the combination of a barrel provided with a chamber, a plunger reciprocating in said chamber, a spring for propelling the plunger forward, a plunger-retracting lever provided with a loose pivoting to allow the raising or extension of the said lever upon its pivot, said lever being provided with a contact surface, and a trigger lever provided with a projecting point adapted to wipe and climb the said contact surface of the said plunger-retracting lever and allowing the discharge of the gun when the projecting point reaches the top of said contact surface, the said projecting point traveling to the rear of said contact surface and again to its initial position in front of said contact surface by reason of the lifting or extension of the said plunger-retracting lever made possible by the said loose pivoting.

5. In a gun of the class described, the combination of a barrel provided with a chamber, a plunger reciprocating in said chamber, a spring for propelling the plunger forward, a plunger-retracting lever pro-

vided with a loose pivoting allowing the extension of the lever against a force normally tending to keep the lever in contracted position, said plunger-retracting lever being suitably connected with a plunger, the said plunger-retracting lever being further provided with an offset contact lip, and a trigger lever provided with a projecting point arranged to wipe the front of the contact lip until it reaches the top of the same when the plunger-retracting lever swings forward allowing the discharge of the gun, the said projecting point being then arranged to travel to the rear of the contact lip and lift or extend the said plunger-retracting lever in passing to the front of the contact lip where it is again in position to wipe and ascend the contact lip.

6. In a gun of the class described, the combination of a barrel provided with a chamber, a plunger reciprocating in said chamber, a spring for propelling the plunger forward, a plunger-retracting lever suitably connected with said plunger for compressing the spring, the said plunger-retracting lever provided with an offset contact lip and having a loose pivoting, a spring for normally keeping the contact lever from being raised or extended on its loose pivot, and a trigger lever provided with a projecting point, the said projecting point adapted to ascend and wipe the contact lip until it jumps off the top thereof to allow the discharge of the gun, the said projecting point traveling to the rear of the contact lip on its return and lifting the same by reason of the loose pivoting to allow the positioning of the projecting point again in front of the contact lip, and means for automatically returning the trigger to its initial forward position when the gun has been discharged.

7. In a gun of the class described, the combination of a barrel provided with a chamber, a plunger reciprocating in said chamber, a spring for propelling the plunger ahead, and means for retracting the plunger, compressing the spring and releasing the same by the single action of a single lever, comprising a plunger retracting lever arranged to swing on a pivot and a trigger lever arranged to swing on a pivot, the said two levers being arranged so that the trigger lever wipes the plunger lever to retract the same for a given distance, whereupon the two levers disengage and cross each other, the said two levers being so arranged that upon the discharge of the gun the trigger lever may return to a position forward of the plunger retracting lever and thereby again be ready to wipe the plunger retracting lever and retract the same.

8. In a gun of the class described, the combination of a barrel provided with a chamber, a plunger reciprocating in said cham-

ber, a spring for propelling the plunger ahead, and means for retracting the plunger, compressing the spring and releasing the same by the single action of a single lever, 5 comprising a plunger retracting lever pivotally supported and a trigger lever pivotally supported, the two levers being arranged so that the trigger lever wipes the plunger retracting lever to retract it for a given distance, whereupon the levers disengage and

the plunger retracting lever springs forward and crosses the trigger retracting lever, the said two levers being also arranged so that the trigger lever may resume its position in front of the plunger retracting lever after the discharge. 15

In testimony whereof, I sign this specification.

WILLIAM F. SCHMIDT.
